UNITED STATES PATENT OFFICE.

NORBERT L. OBERECHT AND FRANK E. PRICE, OF PONTIAC, MICHIGAN.

BUFFER FOR AUTOMOBILES.

Application filed October 15, 1923. Serial No. 668,606.

Our invention relates to buffers for automobiles and an object of our improvements is to provide an ornamental buffer that shall be durable and convenient to construct and 5 assemble.

We secure this object in the construction shown in the accompanying drawings in which—

Fig. 1 is a plan view of a buffer embodying our invention.

Fig. 2 is a sectional detail view of one end of the striker-bar, the constituent parts being in the process of being assembled.

Fig. 3 is a view similar to Fig. 2, the 15 parts being in their assembled positions.

Fig. 4 is a detail section on the line IV—IV Figures 1 and 5.

b, *b*, are the supporting braces, and *a* is the striker-bar, supported and held in position by the braces *b*, *b*.

Each of the braces *b*, *b*, is composed of two flat rods assembled into a Y-formation, the stem of which is composed of portions of said rods bolted or riveted together with 25 their flat sides in contact, said rods then continuously diverging in opposite directions until they are in position to have the cross or striker-bar *a*, secured to them with contiguous portions parallel, as shown in Fig. 1.

30 The cross-bar or striker-bar *a*, is composed of a flat steel bar *a*², rolled at its ends to form vertical eyes *a*³, *a*³, and a similar bar or strip *a*⁴ of any ornamental metal such as aluminum, an alloy of the same or other 35 white metal, or metal of a different color from that of the bar *a*². The bar *a*² is shaped to a convex form outwardly from the vehicle, to which it is secured by the braces *b*, *b*, and the strip *a*⁴ is placed upon 40 its convex surface so that it is in contact throughout the extent of said surface and is drawn tight into place so that any difference of expansion due to a change of temperature or other casual circumstance shall not cause 45 the loosening, or partial separation of the bars *a*² and *a*⁴.

The ends of the strip *a*⁴ are bent tightly 50 around the eyes *a*³, *a*³ at *a*⁵ *a*⁵, and come into contact with the inner surface of the bar *a*² for a short distance as shown at *a*⁶, *a*⁶. The strip *a*⁴ is of slightly less width than the strip *a*² so that anything rubbing against the edge of the cross-bar *a*, shall not tend to separate the strips *a*², *a*⁴ (Fig. 5), and is 55 secured by clips *c*, *c*, and bolts toward the

center of the bar as shown in Figures 1 and 5.

To draw the strip *a*⁴ firmly to place and secure it as a permanent integral portion of the striker-bar *a*, the following expedients 60 and modes of assembly are employed.

The outer rod *b*², of each of the braces *b*, is bent toward its end to a greater curvature than that of the bar *a*, thus forming an elbow or salient portion *b*³, at the point of 65 contact with said bar, as shown in Fig. 2. A bolt is then passed through a bolt hole in the rod *b*² between its end and the elbow *b*³ and through bolt holes in the bar *a*² and strip *a*⁴. The bolt is then drawn up bending 70 the end of the rod *b*² outward with respect to the automobile and the end of the bar *a*, inward. The end of the rod *b*² comes in contact with the strip *a*⁴ where the latter is bent around the eye *a*³ some distance from 75 the surface of the bar *a*², and as the end of the rod *b*², continues to be bent toward the bar *a*², it carries the end of the strip along with it, tightening said strip on the concave 80 surface of the bar *a*².

The bolt *d*, fits tightly against the side of the hole in the strip *a*⁴, which is toward the end of the bar *a*. As the end of the rod *b*² is drawn toward the bar *a*, the latter is bent 85 inward toward the former and the bolt *d*, is inclined from its first position so as to draw outward on the strip *a*⁴ and act to draw the same more closely against the concave surface of the bar *a*².

In the above construction the strip *a*⁴ is 90 somewhat stretched by the forces put upon it and if it expands with a rise of temperature more than the bar *a*², the strain is only partly relieved thereby. The strip *a*⁴ is always, and permanently held against the convex surface of the bar *a*² throughout the extent of said surface with a force at each point sufficient to counteract the effect of any jolt or jar and to prevent rattling or a separation of the contiguous surfaces. 95

The nature of an automobile construction is such as to make it particularly desirable that the buffer, or fender should be of an ornamental nature. To this end the cross-bar has been nickel-plated, but the exposed 100 position and the nature of its use, has caused so rapid deterioration that the expedient is unsatisfactory even after hundreds of thousands of dollars have been expended in 105 experimental work and attempts to make the 110

plating reasonably permanent. By using a strip of ornamental metal, as above described, the ornamental effect is satisfactory and permanent and the construction is more 5 desirable from a utilitarian point of view outside of the ornamental effect.

While steel is used as the material of which buffers are constructed, we have used the word "structural material" in the claims 10 to distinguish from the ornamental material.

What we claim is:—

1. In an automobile buffer a cross-bar consisting of a bar bent to present an outward convex surface and a strip of ornamental 15 material extending along said convex surface and held in contact with said surface by a longitudinal tensile force on said strip.

2. In an automobile buffer, a cross bar consisting of two strips laid together with their 20 broad surfaces in contact and bound together rigidly and permanently to form a single composite bar, one of said strips being wholly of an ornamental material, said composite bar being bent into a curve with said 25 strip of ornamental material on the convex surface.

3. The method of assembling the cross-bar of claim 2 consisting in forming the bar of structural material with rounded ends and 30 winding the strip around said ends.

4. The method of assembling the cross-bar of claim 2 consisting in forming the bar of structural material with rounded ends and winding the strip around said ends and 35 securing the ends of said strip that has passed around the rounded end of said bar.

5. The method of assembling the cross-bar of claim 2 consisting in forming the bar of structural material with rounded ends and 40 winding the strip around said ends and securing the end of said strip that has passed around the rounded end of said bar to the inner surface of said bar by a securing means that puts a longitudinal tension on said strip.

45 6. In an automobile buffer a cross-bar consisting of a bar of structural material, a strip of ornamental material extending along the outer surface of the bar of structural material, a brace-rod engaging said bar on its

inner surface toward the end of said bar and 50 extending from said engaging point toward said end and in a direction inclined outward from the adjacent surface of said bar and a bolt passing through said brace-rod between its contact point and its outer end and 55 through said structural bar and ornamental strip, said bolt being tightened up to draw said cross-bar and brace rod together.

7. In an automobile buffer a cross-bar consisting of a bar of structural material a strip 60 of ornamental material extending along the outer surface of the bar of structural material, a brace-rod engaging said bar on its inner surface toward the end of said bar and extending from said engaging point toward 65 said end and in a direction inclined outward from the adjacent surface of said bar and a bolt passing through said brace-rod between the contact point and its outer end and through said structural bar and ornamental 70 strip, said bolt being tightened up to draw said cross-bar and brace rod together, said structural bar having a rounded end, said strip passing around said end, the end of said brace bar engaging said strip after it 75 has passed around the end of said structural bar and securing the same.

8. The method of assembling the construction of claim 6 which consists in bending the cross-bar inward by tightening up on said 80 bolt.

9. The method of assembling the construction of claim 6, which consists in bending the cross-bar inward by tightening up on said bolt and thereby tensioning said strip by the 85 action thereon of said bolt.

10. The method of assembling the construction of claim 7, which consists in causing the end of said brace-rod to engage said strip after it has passed around said rounded end and at a distance from said bar, and tensioning said strip by the drawing in of said brace rod.

In testimony whereof, we sign this specification.
